UNITED STATES PATENT OFFICE.

FRANK S. OVERACKER, OF STELLA, WASHINGTON.

STANCHION.

No. 849,264.

Specification of Letters Patent.

Patented April 2, 1907.

Application filed July 31, 1906. Serial No. 328,607.

To all whom it may concern:

Be it known that I, FRANK S. OVERACKER, a citizen of the United States, residing at Stella, in the county of Cowlitz and State of Washington, have invented certain new and useful Improvements in Stanchions, of which the following is a specification.

This invention relates to stanchions.

One object of the invention is to provide a stanchion for securing a creature in a stall or place in such manner as to allow more or less freedom of movement whether the animal be standing or lying.

Another object of the invention resides in the provision of a simple, inexpensive, durable, and efficient stanchion embodying such other characteristics as will facilitate its quick and easy manipulation.

With the above and other objects in view the present invention consists in the combination and arrangement of parts hereinafter more particularly referred to, shown in the accompanying drawings, and particularly pointed out in the appended claims.

In the drawings, Figure 1 is a perspective view of my invention. Fig. 2 is a vertical sectional view. Fig. 3 is a detail view of the guiding and limiting member, and Fig. 4 is a detail view of the latch.

Referring now more particularly to the accompanying drawings, it will be seen my improved stanchion may be supported in a suitable framework for erection in a stable, shed, or other place and comprises in its organization base and head members 1 and 2, respectively, connected at suitable intervals by the vertical members 3, with the stanchion disposed in the openings between them. It will thus be understood that my improved

stanchion may be one of a series or that one only may be used. As all the stanchions would be similarly constructed and supported, one only will be herein described.

Secured to opposite sides of the base member 4 are straps projecting beyond each end of the base member to form spaced sets of ears 6 and 7, for a purpose presently explained. A guiding and limiting member 8, preferably U shape, is secured to the head member 4' and projects beyond the ends of the head member, forming at one end thereof the spaced ears 9, which latter aline with the spaced ears 6 to receive the vertical stationary bar 10. Pivoted at its lower end in the ears 7 is a swinging bar 11, whose upper end

moves and is guided in the aforesaid limiting and guiding member 8, the outer end of the latter being closed and slightly contracted to create a binding action upon the movable bar when swung from the stationary bar to limit its movement and prevent accidental backward movement upon its pivot.

When the pivoted bar is thrown into parallelism with the stationary bar to coöperate therewith, means should be provided to hold the pivoted bar against accidental movement upon its pivot, and I therefore provide the pivoted latch member having the legs 13 and the axis 14, upon which latter is loosely mounted the roller 15, designed to rest, normally, upon the upper edge of the guiding and limiting member 8. The upper extremity of the pivoted bar 11 being beveled, as at 16, it permits the bar to pass under the roller 15 and lift the latch upon its pivot *a* until the pivoted bar engages the adjacent end of the head member 4', when the latch will drop and dispose the roller 15 back of the pivoted bar and hold the latter firmly in coöperative relation with the stationary bar 10. It will thus be understood that the roller 15 reduces friction, and that therefore just as soon as the animal's head is in proper position the pivoted bar may be snapped quickly in parallel relation with the fixed bar 10 to hold the creature comfortably against release. While not absolutely necessary, I may employ a spring 16, having one end adapted to coöperate with the latch to limit the upward movement thereof.

My improved stanchion is pivotally mounted, there being upper and lower pivots 17 and 18, respectively, working in the perforations 19 of the eight portions 20 of the corresponding upper and lower U-shaped straps 21, secured in any suitable manner to the base and head members 1 and 2 of the frame in which the stanchion is mounted. It will be seen that the upper pivot pierces the spring 16, but it is to be understood that this spring may be dispensed with, if desired.

What is claimed is—

1. A stanchion comprising a stationary member, a swinging member, a member embracing both members to guide the swinging member and to limit the outward movement of the latter, the outer end of the guiding and limiting member being contracted to create a binding action upon the swinging member when the latter is swung outwardly,

and a latch to hold the stationary and swinging members in operative relation to each other.

2. A stanchion comprising a stationary member, a swinging member, a member embracing both of the aforesaid members to guide and limit the outward swing of said swinging member, the outer end of the guiding and limiting member being contracted to create a binding action therebetween and the swinging member when the latter is thrown outwardly, a latch member to hold the sta-

tionary and swinging members in operative relation, and a roller carried by the latch member to reduce friction between the latter and swinging member.

In testimony whereof I have signed my name to this specification in the presence of two subscribing witnesses.

FRANK S. OVERACKER.
